UNITED STATES PATENT OFFICE.

EUGENE V. MYERS, OF EAST ORANGE, NEW JERSEY, ASSIGNOR TO A. SCHRADER'S SON, INC., OF BROOKLYN, NEW YORK, A CORPORATION OF NEW YORK.

STOPPER FOR WATER-BOTTLES OR THE LIKE.

1,274,437.

Specification of Letters Patent.

Patented Aug. 6, 1918.

Application filed November 12, 1915. Serial No. 61,016.

To all whom it may concern:

Be it known that I, EUGENE V. MYERS, a citizen of the United States of America, residing in East Orange, in the county of 5 Essex and State of New Jersey, have invented certain new and useful Improvements in Stoppers for Water-Bottles or the like, of which the following is a specification:

10 This invention relates to stoppers for water bottles or the like, and aims to provide certain improvements therein.

The invention is particularly directed to that form of stopper in which a neck member is employed which is fastened within the neck of the rubber water bottle. In such constructions a socket member is employed which is connected to the neck member, into which socket member the stopper 15 is screwed. The invention is especially applicable to constructions of this type in which the seat for the stopper is at the upper part of the neck and the packing washer is carried on the upper part of the stopper 20 so that when the stopper is screwed downwardly, water is permitted to enter and discharge from the back through passages or ports which are formed in the socket member immediately beneath the seat. The invention provides in this type of device a construction in which the stopper is always held in engagement with the screw-thread even when the ports are open, so that it is 25 not necessary to adjust the stopper thread to the socket thread in closing the bag. The invention includes certain other features of improvement which will be hereinafter more fully described.

Referring to the drawings which illustrate one form of the invention,—

Figure 1 is a central vertical section of the device.

Fig. 2 is a similar section with the stopper shown in elevation.

Fig. 3 is a plan view.

Referring to the drawings, let A indicate a neck member which is usually constructed of one piece of sheet metal formed with a top wall *a* and side walls *b* which are usually 50 concave to afford a more secure connection with the neck of the water bottle.

Within the neck member A is a socket member B, the latter being connected at its upper end to the top wall *a* of the neck member. Any suitable form of connection

may be used, so long as a seat *c* is provided against which a packing *d* of the stopper C can be compressed.

The stopper C is adapted to screw in the socket member B so that it may be raised 60 and lowered within the latter. The threads on the socket member B and stopper are preferably left-hand threads so that when the stopper is screwed from left to right it will rise and close the aperture *f*, while 65 when it is turned from right to left it will move downwardly, thus removing the packing *d* from the seat *c*.

In order to permit water to flow into and out of the bottle when the stopper is in its 70 lower position, the socket member is formed with apertures *g* which afford passages of sufficient area to permit the easy flow of the water.

According to the present invention I provide a construction in which the stopper continuously engages the thread of the socket member, so that the simple operations of screwing to right or left will close or open the device. It has heretofore been 75 proposed to provide a stopper which screws upwardly to close the bottle, but in such constructions the stopper is opened by screwing it entirely out of its socket member and permitting it to hang within the 80 bag. In such construction there is difficulty in causing the stopper to engage its thread when it is desired to close the bag, and this difficulty is increased by the fact that an outward pull must be maintained on the 85 stopper while the act of engaging the thread takes place. This is contrary to the normal operation of such devices, and in practice the ordinary user is apt to be confused by the difference in conditions. According 90 to the present invention no pull need be exerted on the stopper, and no fitting of the threads is necessary. It is only requisite that the stopper be turned by its handle in one direction to close it, and in the opposite direction to open it.

Preferably some stopping means is provided for forcibly preventing the disengagement of the stopper from its socket member, and this may be either the conformation of the handle which causes it to strike the upper wall *a*, or a flange, such as *h*, may be provided at the lower part of the socket member which is adapted to engage the bottom wall of the stopper. Other 105 110

suitable means may be employed for this purpose.

When the water bag is emptied substantially all of the water will discharge through the passages *g*, but if the stopper is constructed with an open bottom, as shown, a small amount will be retained in the body of the stopper. To enable this to be emptied when the bottle is turned upside down I provide an aperture or apertures *j*.

While I prefer to use the neck member as a means for connecting the socket member to the water bottle, it will be noted that other constructions may be adopted so long as the connection between the socket member and the water bottle is such as to permit water from the bottle to flow through passages *g* when the stopper is lowered.

While I have shown and described one form of the invention, it will be understood that I do not wish to be limited thereto, since various changes may be made therein without departing from the spirit of the invention.

What I claim is:

1. A device of the character described comprising a neck member, a socket member connected at its upper end to said neck member, a seat at the point of juncture of said parts, said socket member being formed with passages below said seat, and a stopper screwing in said socket member, said stopper adapted to make a tight joint with said seat when in its uppermost position, and to uncover said passages when in its lower

position, and means for preventing said stopper from screwing completely out of said socket member.

2. A device of the character described comprising a sheet metal neck member having an upper wall, a socket member having its upper end connected to said wall, a seat at the point of juncture of said parts, said socket member being formed with passages below said seat, and a stopper screwing in said socket member, said stopper adapted to make a tight joint with said seat when in its uppermost position and to uncover said passages when in its lower position, and means for preventing said stopper from screwing completely out of said socket member.

3. A device of the character described comprising a sheet metal neck member having an upper wall and side walls depending therefrom, a socket member lying within said side walls and having its upper ends connected with said upper wall, a seat at the upper part of said socket member, a passage below said seat, a screw-threaded stopper engaging said socket member, and means for preventing said stopper from screwing completely out of said socket member.

In witness whereof, I have hereunto signed my name in the presence of two subscribing witnesses.

EUGENE V. MYERS.
